ROCKABLE ROLLER ASSEMBLY

Otto T. Hovarter, Ashley, Ind.

Application September 11, 1941, Serial No. 410,390

3 Claims. (Cl. 193—42)

This invention relates to rockable roller assemblies for use in connection with casket receiving and supporting frames.

One of the prime objects of the invention is to design a light-weight, quickly removable roller assembly to facilitate placing the conventional casket on the frame, and to obviate the necessity of pallbearers walking alongside the excavation and the dangers attendant thereto.

Another object is to provide a rockable roller assembly unit which facilitates the sliding of the casket onto the frame, which is readily removable as a unit for transportation and storage, which is inexpensive to manufacture and assemble, and which is applicable to the different makes of casket lowering apparatus and/or frames.

With the above and numerous other objects in view as will appear as the specification progresses, the invention resides in certain novel features of construction, and in the combination and arrangement of parts as will be hereinafter more fully described and claimed.

In the drawing:

Fig. 1 is a fragmentary, side elevational view of a conventional casket receiving frame with my rockable roller assembly mounted thereon;

Fig. 2 is a top plan view;

Fig. 3 is a transverse, part sectional end view taken on the line 3—3 of Fig. 2; and

Fig. 4 is an enlarged sectional side elevational view showing the frame and roller assembly, the broken lines showing the assembly in tilted position.

Referring now to the drawing in detail wherein is shown the conventional receiving frame B comprising side and end members 8 and 9, respectively, connected by means of corner castings A which are supported on a foldable corner support C, these corner supports forming the subject matter of a separate application filed by me of even date herewith; and I, therefore, do not deem it necessary to show or describe this in detail in the instant application.

The roller assembly is removably mounted on the tubular end bar 9 as shown, and comprises a pair of horizontally disposed, spaced apart tubular members 10 and 11, respectively, the ends of which are curved and bent at right angles to the main body, these ends terminating in saddles 12 which are shaped to fit and rock on the end bar 9, each saddle terminating in downwardly projecting end sections 13 and for a purpose to be presently described.

The pronged ends of the saddles extend a pre-

determined distance below the rails 9, and a vertically projecting stop member 14 is provided on the foldable corner support C and extends into the space between the end sections 13 so that as the assembly is rocked, as indicated in broken lines in Fig. 4 of the drawing, the ends 13 of the saddle will engage the stop 14 provided on the support C, and limit the swing or rocking movement.

Rubber rollers 15 are revolvably mounted on the members 10 and 11 in spaced relation, and these rolls are held in proper set position by means of collars 16 which are provided with set screws 17 as usual.

These roller assembly units can be mounted on either end of the frame, and to suit the approach to the excavation.

In practice, and when the apparatus is set up for use, the roller assembly is tilted outwardly and downwardly from the frame. This eliminates the possibility of the casket (not shown) striking the end member 9 of the frame as it is carried forward; and when the head end of the casket engages the rollers 15, it slides slightly upward, engaging the companion rollers on the opposite arm; thence sliding horizontally over the frame, and in turn engaging and riding on the intermediate rollers (not shown) provided on the frame, making it unnecessary for the persons carrying the casket to walk alongside the grave excavation, and the sliding action of the casket will be smooth and easy.

From the foregoing description it will be readily apparent that I have perfected a very simple, practical, and convenient rockable roller assembly unit which can be easily and economically manufactured and assembled, and which can be readily transported from place to place or stored in a very limited space.

What I claim is:

1. A quickly removable, rockable unit mounted on a casket receiving frame and comprising spaced apart, horizontally disposed bars terminating in saddles detachably engaging the end rail of the casket receiving frame, roller members journaled on said bars, and depending legs forming a part of each saddle and engageable with a stop for limiting the rocking movement of said unit.

2. A rockable unit adapted to be mounted on a casket receiving frame and comprising spaced apart, horizontally disposed bars having curved end sections terminating in open saddles for detachable engagement with the end rail of casket receiving frame; rollers mounted on said bars

in spaced apart relation; collars for securing said rollers in position, and spaced apart depending legs forming a part of each saddle and engageable with a stop for limiting the rocking movement of the unit.

3. A quickly removable, rockable roller assembly unit adapted to be mounted on the end rail of a casket receiving frame and comprising horizontally spaced bars, the ends of which con-

verge and terminate in open saddle members adapted to fit over the end rail of the frame, said saddles terminating in downwardly projecting prongs depending below the end rail of the casket receiving frame and adapted for engagement by a stop; rollers revolvably mounted on said bars; and means for preventing endwise movement of the rollers on said bars.

OTTO T. HOVARTER.
